UNITED STATES PATENT OFFICE.

MAURICE LACHMAN, OF NEW YORK, N. Y., ASSIGNOR TO STRUCTURAL PRESSED STEEL WHEEL COMPANY, INC., OF NEW YORK, N. Y., A CORPORATION OF NEW YORK.

METAL WHEEL.

1,215,552.

Specification of Letters Patent. Patented Feb. 13, 1917.

Application filed June 12, 1916. Serial No. 103,145.

To all whom it may concern:

Be it known that I, MAURICE LACHMAN, a citizen of the United States, and a resident of New York, in the county of New York and State of New York, have invented certain new and useful Improvements in Metal Wheels, of which the following is a specification.

My present invention relates to metal wheels the main portions of which are made of sheet metal and its object is to provide a light construction of great strength and low cost of manufacture. The wheel may be used for light automobiles, baby carriages or any other use to which it is applicable.

To these ends the invention consists in the improved construction of wheel herein-after more particularly described and then specified in the claims.

In the accompanying drawings, Figure 1 is a side elevation of a wheel embodying my present invention.

Fig. 2 is a side elevation of the disk used to provide the rim, hub and spoke portions of the wheel.

Fig. 3 is an edge view of the same.

Fig. 4 is an enlarged transverse cross-section taken on the line 4—4 Fig. 1.

Fig. 5 is a still further enlarged fragmentary view of the edge of the material surrounding one of the openings in the disk and showing one of the means for thickening the edges prior to securing the same to the disk.

Fig. 6 is a similar view after clamping the thickening member to the disk.

Fig. 7 illustrates in edge view the member employed in the form shown in Fig. 1 for thickening the edge of the material around the openings.

Fig. 8 is a plan view of a part of the spoke portion prepared for thickening the edge according to a modification.

Fig. 9 is a similar view showing a further stage in the operation.

Fig. 10 is an enlarged transverse section through the spoke portion shown in Fig. 9 and showing the reinforcing member applied.

Fig. 11 is an enlarged transverse section through one edge of a spoke member and illustrates a further modification in the manner of thickening the edge.

Fig. 12 illustrates a still further modification.

Fig. 13 illustrates a further modification.

According to one manner of carrying out my present invention and especially where the wheel is intended merely for light loads the main part of the wheel comprises but a single sheet metal disk A (Figs. 2 and 3) of any desired thickness. This disk is provided with a plurality of openings 1 preferably so disposed as to leave a continuous rim portion 2, a hub portion 3 and integral spoke members 4 connecting the hub and rim portions. The openings 1 may be of any desired contour and of any suitable number. The hub portion is provided with the usual opening 5 for the axle or other supporting spindle.

If the wheel was constructed with a plain disk as so far described while it might have sufficient strength to support light loads it would provide little if any resistance to lateral strains. To reinforce the disk A to take these strains I thicken the edges preferably completely around the openings 1, that is the edges of the rim, spokes and hub bounding the opening. This thickening of the edges may be accomplished in a multiplicity of ways, the effect being to attain an I beam section of the spoke members and also the rim portion if desired.

As above stated, a single disk might be used as a wheel, or a number of the same might be employed together to make a wheel. It will be understood that in wheels which comprise more than one disk the edges of each disk around the spoke openings are separately thickened or reinforced, that is, each disk and its reinforcement will be a unit and wherein the term "single" disk is employed in the claims it does not imply that the wheel as a whole consists of but one disk but the expression is used to define the distinction that a single disk or each disk is provided with the reinforced edge independent of the other disk or disks, and is used to distinguish over that class of patents in which the edges of the spoke portions or some parts of two members are joined either by a folded edge or a separate member folded over the meeting edges. This class of patents may be instanced by the patent to Craven No. 915,829 in which the reinforcing is secured primarily by the shape given to the spokes themselves.

This thickening of the edges and consequent reinforcing of the disk is attained in

- the form shown in Figs. 1, 4, 5, 6 and 7 by means of an endless strip 6 having its abutting ends 7 preferably securely united together and the whole bent to the shape of the opening 1 and of such size that it bears against the edge of the disk around the opening as indicated in Fig. 5. By means of a suitable press the edges of the member 6 are then bent over and against the opposite surfaces of the disk as indicated in Fig. 6. Also preferably the outer edge of the disk is similarly thickened by means of the annular member 7 and if desired the opening 5 in the hub may be similarly reinforced.
- 15 Holes 8 are provided in the hub portion 3 for attachment of standard hubs as is usual in the art. The rim 2 may be provided with any style of metal tire or rubber tire carrying element of any desired type secured to the rim 2 in any suitable manner, this feature forming no part of my present invention.
- 20 Figs. 8 to 12 inclusive illustrate some of the other ways in which the edges surrounding the openings 1 may be thickened and reinforced.
- 25 In the modification shown in Figs. 8, 9 and 10 the edges of the hub 3, spoke 4 and rim 2 surrounding the opening are split for a short distance inward and the edge portions bent in opposite directions forming ears 9, some projecting laterally from the plane of the disk A on one side while the others project similarly from the opposite side. Continuous members 10 similar to the members 6 in the previous form are clamped around and connect the various projecting ears 9 on opposite sides of the disk.
- 30 In the modification shown in Fig. 11 the disk at the edges around the openings 1 is provided with a flange 11 projecting laterally from one surface and the thickening member 12 is clamped over this flange and provided with a rib 13 engaging and projecting from the opposite surface of the disk.
- 35 In Fig. 12 the thickened edge is integral with the disk, it being provided by doubling the metal at the edge surrounding the opening back upon itself in any desired manner in a suitable press.
- 40 The doubling of the metal around the openings to thicken the edges by the material itself may also be done as indicated in Fig. 13 in which the metal is so folded or shaped

as to form a hollow tube 15 which bounds the opening.

55 It will be understood that the various ways shown and described of carrying this invention into practice are for the purpose of illustration only and are not to be considered as limiting the scope except as may be specified in the appended claims.

That form of my invention illustrated in Fig. 13 and hereinbefore described is not specifically claimed herein since it forms the subject of an application for patent filed by me as a division hereof on the 12th day of July, 1916, Serial No. 108,875.

What I claim as my invention is:—

1. A metal wheel comprising a sheet metal disk having a plurality of openings 70 therein to form a hub portion, a rim portion and connecting spoke members, the edges of the rim, spoke and hub portions surrounding said openings being thickened to reinforce said material and form a spoke member substantially I-shaped in cross section.

2. A metal wheel including a single sheet metal disk having a plurality of openings 80 therein to form hub, rim and spoke portions and a separate member secured to the material of the disk at the edge of said openings and adapted to thicken said edges on both faces of said disk and reinforce said disk against lateral strains.

3. A metal wheel including a single sheet 85 metal disk having openings therein to form rim, hub and spoke portions and a thickening element on the edge of the material completely surrounding each opening and projecting laterally in opposite directions from 90 the faces of the disk.

4. In a metal wheel, a sheet metal disk having openings to form spokes integral with the continuous rim and center, combined with a continuous strip of metal bent 95 around the edge of the metal constituting the edge of the disk around said openings and against the opposite surfaces.

Signed at New York, in the county of New York and State of New York, this 10th day of June, A. D. 1916.

MAURICE LACHMAN.
